UNITED STATES PATENT OFFICE

HARRY BUTLER FLOWER, OF BAYVILLE, NEW YORK

SELF-RAILING TRACKWAY

Application filed May 18, 1932. Serial No. 611,999.

This invention is a self-railing trackway; especially adapted to the self railing of cars or trains upon toy railways, such as miniature electric railways with current supplied through the wheel rails and a central third rail.

The general object of the invention is to afford a simple, convenient and effective construction of miniature railway which will operate automatically, by a mere longitudinal rolling along the trackway, to place cars or whole trains properly upon the tracks, referring both to the initial setting or railing of the cars and trains or to the replacing or rerailing the same when derailed. The cars may thus be manually lifted, singly or in groups, and set approximately in position and then shifted correctly on to the rails by simply rolling them along upon the device of this invention. Heretofore, so far as I am aware, it has been necessary to give individual and manual attention to the placement upon the tracks of each pair of wheels or wheel truck, throughout the length of the train; and the present invention eliminates this troublesome requirement and provides a railway track unit, which may be inserted at a dispatching or other convenient point on the system, to facilitate the quick applying of the rolling stock to the tracks. A special object is to adapt the principles of the invention to use with an electric railway having a central third rail.

Other objects and advantages of the invention will be pointed out in the hereinafter following description of an illustrative embodiment thereof or will be understood to those conversant with the subject. To the attainment of such objects and advantages the present invention consists in the novel self-railing railway construction and the novel features of combination and arrangement herein illustrated or described.

In the accompanying drawings Figure 1 is a perspective plan view of a sufficient length of railway construction to disclose the principles of the present invention.

Fig. 2 is a vertical longitudinal section taken along the central line 2—2 of Fig. 1.

Fig. 3 is a vertical transverse section taken along the line 3—3 of Fig. 1.

Fig. 4 is a vertical transverse section taken along the line 4—4 of Fig. 1.

Fig. 5 is a top plan view partly in diagram showing the self-railing action of the invention.

Fig. 6 is a view similar to Fig. 5 showing a car being railed from a different initial setting.

Fig. 7 is a top plan view of the invention with the showing of car and wheels omitted.

Describing the invention as applied to a toy electric railway, Fig. 1 shows a pair of spaced apart rails 10 of ordinary type. These may for example be produced from sheet metal, and the rails are shown held in proper parallel relation by cross supports or metallic ties 11, indicated also in Fig. 2. A third rail 12 carrying current to a contact underneath the car or engine is shown mounted centrally between the rails and held by the tie 11, with an insulation 13 interposed. As is usual in such railways the construction is provided in units of standard length, and each unit may be coupled to the succeeding one by means of coupling rods or pins 14 engaged within or projecting from the ends of rails 10 and adapted to be inserted in corresponding aligned recesses in the next rail unit; while the third rail may have a similar coupling rod 15 for a similar purpose.

A railway car 17 is indicated in dotted outline in Figs. 5 and 6, with a front truck 18 having its four wheels properly engaged upon the rails and a rear truck 19 derailed, with its wheels offset laterally from the tracks; while the same car is shown at 17^a, and the same trucks in full lines at 18^a and 19^a, advanced further rightward along the trackway and with the rear truck about to assume its proper position upon the rails.

Referring now to the self-railing device of this invention, this is shown provided as a single or unitary structure or unit 20 adapted to be inserted between and coupled to ordinary trackway units at each end. It thereby becomes a fixed part of the trackway, preferably without movable parts, and is such as not to interfere with traffic in either direction,

while always ready for tracking a derailed or newly placed car or train. The self-railing unit may be built up but preferably is partly cast or struck to shape.

The self-railing unit 20 hereof may comprise a base 21 in the nature of a generally flat plate having downward flanges or marginal supporting portions to aline the unit at the same level with the regular trackway units. Upstanding above the base or plate 21 are shown the following constructional elements. At each end are spaced rail sections 22 alining with the regular rails 10 and perforated to receive coupling rods 14 or having such rods projecting for coupling to another unit. The end rail sections 22 terminate a fractional distance from the ends of the unit, and between their terminations, at each side, is located a side section 23, while between the two side sections 23, 23 is a middle section 24 upstanding like an island from the base. The several sections 22, 23 and 24 may be symmetrically arranged both laterally and longitudinally so that a car or train may be set approximately in place and run on to the rails from either side and in either direction.

The detail construction of the several sections 22, 23 and 24 may be substantially as shown. Thus a groove 25 is shown between the inclined extremity of each rail end section 22 and the inclined edges 26 of the side sections 23; and preferably each groove is a notch of shallow depth and each edge is bevelled to facilitate the riding up of the wheel to where its flange passes into the groove. By this arrangement a wheel flange approaching in the converging space between a rail end section 22 and the inclined edge 26 of a side section will be adjusted or cammed inwardly toward the rail, and will eventually roll up upon the bevel of the edge 26 and finally into and through the groove 25, to drop into place upon the straight edge 27 of the side section, which edge is in alinement with the rail end sections 22.

Between each side section and the middle section 24 is a full depth groove 29 along which a properly positioned wheel flange may travel. The middle section at each end is formed with converging side edges 30, each of these inclined edges being also bevelled similarly to the edges 26 of the side sections. There are thus four inclined and bevelled side edges 30 to the middle section and these are substantially parallel respectively with the four inclined and bevelled edges 26 of the side sections, and cooperate therewith in restoring the opposite wheels of a pair of trucks to the rails, since, when each wheel is being guided toward its rail by the inclined edge 30 of the middle section, the opposite wheel is being similarly guided and lifted over its rail by the inclined edge 26 of a side section.

In the case of an electrically energized railway, the following electrical arrange-

ments may be provided coordinating with the third rail 12 of the usual track unit. The special self railing unit 20 is shown as provided at each end with a third rail stretch 35 formed with a coupling rod 15 or recessed to receive one. The end stretch 35 is shown as a separate metal piece insulated from the base 21 by an insulating sheet 36. As best seen in Figs. 2 and 4 the stretch 35 is secured by an attaching screw 37 passing through the insulation 36 and itself insulated at its under side by a washer 38. Between the washer and screw head is held the eye 39 of an insulated wire or connector 40 having at its other end an eye 41 to conduct electricity to a third rail middle stretch 43, which latter is shown as accommodated in a groove formed centrally through the middle section 24 of the trackway unit. The extremities of the third rail middle stretch 43 are shown sharpened at 44 and bevelled to aline with the bevelled inclined edges 26 of the section 24. The stretch 43 is insulated from surrounding parts by an insulating sheet 45, and as shown in Figs. 2 and 3 the parts may be secured by one or more attaching screws 46 extended upwardly into the middle stretch 43, the screw itself being insulated by an underneath washer 47 and having the eye 41 inserted and held between the screw head and washer. By this arrangement the middle third rail stretch is energized along with the usual third rails of the trackway; and the described connecting arrangement may be duplicated at both ends of the unit 20 so that the current will be conducted on beyond to the third rail 12 of the next railway unit.

With a toy railway the operation may be as follows. Taking for example the case of several cars coupled together, perhaps with a locomotive, such a train may be lifted bodily, as by the end cars, and set approximately in position upon the trackway, for example to the left of the special railing unit, and without particular attention to the placing of the individual wheels upon the tracks. Without lifting the hands from the train it need only be at once shifted toward the right, so that all wheels and trucks will roll longitudinally along the special railing unit. In this action all of the wheels are caused to roll on to the proper tracks, either as shown in Fig. 5 or as shown in Fig. 6 according to the position in which the trucks happen to stand. As soon as the cars have traversed the special unit the train is ready to be operated. Instead of pulling the train manually along the trackway it may be set in approximate position, and the current thereupon applied to cause the advance of the locomotive, its traction serving to drag along the cars of the train, which are thus properly set upon their rails throughout the length of the train. The improvement is simple, strong and durable and

is found to be remarkably effective and convenient for the purposes stated.

There has thus been described a self-railing trackway attaining the objects and advantages referred to; since however various features of combination and arrangement may be modified without departing from the invention it is not intended to limit the invention to such features except so far as set forth in the appended claims.

10 What is claimed is:

1. A self-railing trackway construction, comprising an interrupted rail end section at each side, upstanding opposite side sections each having a straight inner edge alining with said end section and an inclined edge converging with the adjacent end section, and with a wheel flange groove between the end and side sections, and an upstanding middle section spaced from the rails and having diverging opposite inclined edges each converging with the adjacent end section.

2. A trackway construction as in claim 1 and wherein each side section has an inclined edge at both ends converging with the adjacent section and with shallow notches between sections, and the middle section has opposite inclined edges at both ends also converging with the adjacent end sections.

3. A trackway as in claim 1 and wherein is a shallow notch between each end and side section, and each side section has its inclined edge bevelled to slant up to such notch.

4. A unitary self-railing miniature trackway unit, comprising a detachable base having fixedly mounted thereon an interrupted rail end section at each side, with coupling means for interconnection to contiguous trackway units, upstanding opposite side sections each having a straight inner edge alining with said rail end sections and an inclined edge converging with the adjacent end section, and with a shallow wheel flange notch or groove between the end and side sections, and an upstanding middle section spaced from the rails and having diverging opposite inclined edges each converging with the adjacent end section.

5. A unit as in claim 4 and wherein each inclined edge of the side and middle sections is also bevelled.

6. A unitary self-railing miniature trackway unit, comprising a detachable base having fixedly mounted thereon an interrupted rail end section at each side, with coupling means for interconnection to contiguous trackway units, upstanding opposite side sections each having a straight inner edge alining with said rail end sections and an inclined and bevelled edge converging with the adjacent end section, and with a shallow wheel flange notch or groove between the end and side sections, and an upstanding middle section spaced from the rails and having diverging opposite inclined edges each converging

with the adjacent end section, the inclined edges of the middle section being substantially parallel to the inclined edges of the side section, respectively, to cooperate in the railing of opposite wheels.

7. A unitary self-railing miniature trackway unit, comprising a detachable base having fixedly mounted thereon an interrupted rail end section at each side, with coupling means for interconnection to contiguous trackway units, upstanding opposite side sections each having a straight inner edge alining with said rail end sections and an inclined edge converging with the adjacent end section, an upstanding middle section spaced from the rails and having diverging opposite inclined edges each converging with the adjacent end section, an end stretch of third rail interrupted short of the middle section, a middle stretch of third rail at said middle section, both of said stretches being insulated, and insulated connections between such stretches.

8. A unit as in claim 7 and wherein the middle section is centrally grooved to accommodate the middle stretch of third rail, and the end stretch of third rail is adapted to be coupled with the third rail of a regular trackway unit.

In testimony whereof, this specification has been duly signed by.
